ADJUSTABLE FLEXIBLE BAND

Nino Bisso, New York, N. Y.

Application October 18, 1946, Serial No. 704,251

6 Claims. (Cl. 59—79)

1

The present invention relates to flexible bands of the link type intended primarily for use as wrist watch straps or bracelets.

The primary object of the present invention is the provision of a flexible band comprising a series of links having means in the links themselves for increasing or decreasing the length of the band to suit the wearer's requirements in respect to the size of the latter's wrist.

Another object of the invention is to provide an adjustable flexible band of the link type which is of simple construction and which can be readily adjusted by the wearer either to increase or to decrease the length of the band without the use of an adjustable buckle or connector.

The above and other objects, features and advantages of the invention will be fully understood from the following description, reference being had to the accompanying illustrative drawings.

In the drawings:

Fig. 1 is a side edge view of an adjustable flexible band embodying the present invention, the links being shown in their band-contracting positions;

Fig. 2 is a side edge view of a portion of the band showing the links in their extended or band-expanding relation;

Fig. 3 is a top plan view, on a greatly enlarged scale, of a few of the links of the band;

Fig. 4 is a sectional view on the line 4—4 of Fig. 3;

Fig. 5 is an exploded perspective view, on a greatly enlarged scale, of two adjacent links and a companion pivot pin.

Referring now to the drawings in detail, the adjustable flexible band 10 of the present invention comprises a series of links 12 disposed in end to end relation and pivotally and adjustably connected to each other in said relation as hereinafter more particularly described. As here shown, each link 12 is open at its opposite ends and overlaps the adjacent ends of the adjacent links in the band. In the specific illustrated embodiment of the invention, links 12 are hollow and taper longitudinally and are assembled so that the narrower end of one link is received within the wider end of the adjacent link. As will be readily understood, said links are preferably formed of sheet metal.

Each link 12 comprises a top wall 14, a bottom wall 16, and opposite side walls 18. A pair of laterally aligned openings are provided in the side walls 18 of each link and a pair of longitudinal slots 22 which are in lateral alignment,

2

are provided in side walls 18 and are disposed in longitudinally spaced relation to openings 20. A pivot pin 24 is secured in openings 20 of one link and engages the adjacent link in slots 22 of the latter for pivotally connecting the adjacent links to each other in such manner as to permit relative movement of said adjacent links longitudinally of the band. It will be noted that by reason of the engagement of the pins 24 of the

links in the slots 22 of the adjacent companion links, respectively, of the band, adjacent links have a limited relative movement in opposite directions longitudinally of the band, said movement being determined by the length of slots 22.

15 Interengaging means are provided on adjacent links for releasably holding them against relative movement in either direction longitudinally of the band. Said interengaging means comprises companion relatively movable parts on adjacent

links 12, respectively, one of said parts being constituted by the companion pivot pin 24 and the other of said parts being constituted by a detent member 26 which is secured within each link at the bottom 16 thereof laterally between the

25 slots 22 in position to engage the companion part or pivot pin 24 of the adjacent link. As here shown each detent member 26 has an intermediate rounded surface portion 28 which projects slightly above the lower edges of the companion slots 22. One end 30 of the detent member 26 is secured to the bottom 16 of the link in any suitable way, as by solder, self-eyeleting, riveting, etc., while the opposite end 30 of the detent member is not secured and left free to move

30 longitudinally of the link. Detent members are formed of spring metal and thus constitute resilient means to hold the adjacent links releasably in adjusted position. By reference to Fig. 4 it will be understood that the detent members 26 are adapted to hold the companion pivot pins 24 releasably in position at either of the opposite ends of the companion slots 22, respectively, and it will be understood that said detents oppose or resist free relative movement of

35 adjacent links longitudinally of the band, but allow relative longitudinal movement of the links in response to a pushing and a pulling force exerted endwise on adjacent links for decreasing and increasing, respectively, the length of the band. As shown in Fig. 4, the link 12 at the right hand end of the link assemblage is positioned with respect to the adjacent, or middle link of the assemblage in the relation in which the two links are in band-increasing positions,

40 45 50 55 while the other two links of the assemblage are

in their relative positions for decreasing the length of the band. When the links 12 are moved toward each other or away from each other longitudinally of the band, for decreasing or increasing the length of the band, pins 24 snap over the rounded portions 28 of the companion resilient detent members 26. As the relative longitudinal movement of each pair of adjacent links 12 is comparatively small, a desired small adjustment of the length of the band is thus provided for, while on the other hand a substantial increase or decrease in the length of the band, as the case may be, can be obtained by reason of the aggregate of the relative adjustments of the links throughout the length of the band.

As described above, the links 12 taper longitudinally and it will be noted that they not only taper in width as hereinbefore indicated, but also taper in depth, that is, in respect to the dimension between the top 14 and the bottom 16 of the link. Further it will be observed that at the narrow end of each link 12 the side walls 18 terminate in edges 32 which are spaced somewhat from the inner surface of the top wall 14 of the adjacent link to provide clearance between adjacent links so as to allow relative pivotal movement of said adjacent links, whereby the band may conform readily to the curvature of the wearer's wrist. In this connection, it will be observed that the bottom 16 of each link terminates short of the adjacent end of the link, as indicated at 34, to permit said pivotal movement of adjacent links. Further it will be noted that each link 12 may be formed in one piece by bending a properly shaped sheet metal blank into the form of the link, the meeting edges of the link-forming blank being at the bottom 16 of the link, as indicated at 36 in Figs. 3 and 5.

It will be understood that the band 10 is preferably made up entirely of the links 12 which are adjustable longitudinally of the band in opposite directions, as described above, it being within the scope of the present invention, however, to omit the adjustable connection in some of the links of the band if so desired. The band may be provided with any suitable means for connecting the band to a wrist watch indicated at W in Fig. 1, when the band is used as a wrist watch band or for connecting said band to any other device, for example, a bracelet ornament when the band is used for that purpose. Any suitable releasable or expandable and contractable connecting device may be provided on the band to enable the latter to be put on and taken off the wearer's wrist, such devices being well known and therefore indicated only generally at 38 in Fig. 1.

While I have shown and described the presently preferred embodiment of the invention, it will be understood that the invention may be embodied otherwise than as herein specifically illustrated or described, and that various changes in the details of construction, in the shape of the links, and in the arrangement of the parts may be made without departing from the underlying idea or principles of the invention within the scope of the appended claims.

Having thus described my invention, what I claim and desire to secure by Letters Patent is:

1. An adjustable flexible band comprising a plurality of links pivotally connected to each other at their adjacent ends, respectively, by pivot pins, adjacent links being each provided with a pair of lateral spaced slots in which the pivot pin between adjacent links has a limited move-

ment in opposite directions longitudinally of the band, and means carried by one of said links and adjustably engageable with the companion pivot pin of the adjacent link for releasably holding said companion pivot pin at either of the opposite ends of said pair of slots.

2. An adjustable flexible band comprising a series of links disposed in end-overlapping relation longitudinally of the band, each of said links having a pair of lateral openings and a pair of slots spaced from said openings longitudinally of the link, a pivot pin secured in said lateral openings of one of the links and engaging the companion adjacent link in said slots for pivotally connecting adjacent links to each other, and means carried by said links and adjustably engageable with the pivot pins of companion links, respectively, for releasably holding said pivot pins, respectively, at either of the opposite ends of the slots of said links, respectively.

3. An adjustable flexible band comprising a series of links disposed in end-overlapping relation longitudinally of the band, said links being open at their opposite ends and one end of each link projecting into the adjacent end of the adjacent link, each of said links having a pair of lateral openings and a pair of slots spaced from said openings longitudinally of the link, a pivot pin secured in said lateral openings of one of the links and engaging the companion adjacent link in said slots for pivotally connecting adjacent links to each other, and means carried by said links and adjustably engageable with the pivot pins of companion links, respectively, for releasably holding said pivot pins, respectively, at either of the opposite ends of the slots of said links, respectively.

4. An adjustable flexible band comprising a series of links disposed in end-overlapping relation longitudinally of the band, said links being open at their opposite ends and one end of each link projecting into the adjacent end of the adjacent link, said links being relatively movable in opposite directions longitudinally of the band, and interengaging means on adjacent links, respectively, for releasably holding them against relative movement in either of said directions longitudinally of the band, said interengaging means of adjacent links including relatively movable companion parts carried by adjacent links, respectively, one of said companion parts also providing means for pivotally connecting the adjacent links to each other in said end-overlapping relation.

5. An adjustable flexible band comprising a series of links disposed in end-overlapping relation longitudinally of the band, said links being relatively movable in opposite directions longitudinally of the band and interengaging means on adjacent links, respectively, for releasably holding them against relative movement in either of said directions longitudinally of the band, said interengaging means of adjacent links including relatively movable companion parts carried by adjacent links, respectively, one of said companion parts also providing means for pivotally connecting the adjacent links to each other in said end-overlapping relation.

6. An adjustable flexible band comprising a series of links disposed in end-overlapping relation longitudinally of the band, said links being relatively movable in opposite directions longitudinally of the band and interengaging means on adjacent links, respectively, for releasably holding them against relative movement in either of

said directions longitudinally of the band, said interengaging means of adjacent links including relatively movable companion parts carried by adjacent links, respectively, one of said companion parts also providing means for pivotally connecting the adjacent links to each other in said end-overlapping relation, the other of said companion parts comprising a detent which resists free relative movement of adjacent links longitudinally of the band but which allows such movement in response to a pushing or a pulling force exerted endwise on adjacent links for decreas-

ing and increasing, respectively, the length of the band.
